UNITED STATES PATENT OFFICE.

WALLACE WILSON, OF DENVER, COLORADO.

WATER-HEATER.

1,248,969.

Specification of Letters Patent.

Patented Dec. 4, 1917.

Application filed April 20, 1916. Serial No. 92,414.

To all whom it may concern:

Be it known that I, WALLACE WILSON, a citizen of the United States, and a resident of the city and county of Denver, in the 5 State of Colorado, have invented certain new and useful Improvements in Water-Heaters, of which the following is a full, clear, and exact description, such as will enable others skilled in the art to which the 10 invention appertains to make and use the same.

My invention relates to improvements in water heaters, and the invention has for its object the provision of a water circulating 15 medium which may be applied to a cooking stove, or other heating unit for the utilization of the heat emanating from the stove, or other heating unit for the purpose of heating water.

20 Another object of the invention is to provide means for utilizing the same heat used for cooking, or other purposes for heating water, thereby obviating the necessity of employing an independent heating 25 source for the water.

Another object of the invention is to provide means for application to a stove, without altering the construction of the 30 stove, for utilizing the same heat units to heat water, and which means will not interfere with the primary use of the stove or in any manner detract from the efficiency 35 of the stove in its primary use.

With these and other objects in view, 40 the invention will be described with reference to the accompanying drawing, which forms a part hereof.

In this drawing, Figure 1 is a plan view 45 of a cook stove, showing the water heating attachment applied thereto; Fig. 2 is an elevational view of the storage tank used in connection with the invention; Fig. 3 is an enlarged plan view of one of the circulating units; and Fig. 4 is a cross sectional view 50 of the circulating unit, taken on the line 4—4, Fig. 1.

Corresponding and like parts are referred 55 to in the following description and indicated in all the views of the accompanying drawing by the same reference characters.

Let the numeral 5 represent a cook stove which employs gas as the fuel, the same being provided with the usual burners 6, above which a grating 7 is disposed. This grating 55 7 is usually removable with convenience. The numeral 8 designates the water circu-

lating unit in its entirety. One of these units is positioned above each burner 6 below the grating 7, and the circulating units are all connected in communication with each other by means of the connecting pipes 60 9, 10 and 12. A supply pipe 13, leading from the bottom of the storage tank 14, communicates with the first circulating unit 8 of the series, while an eduction pipe 15 65 leads from the last heating unit 8 into communication with the upper extremity of the storage tank 14. A feed pipe 16 supplies the storage tank 14, the same entering the top of said tank and having its discharge 70 extremity extended close to the bottom of said tank, whereby the water is discharged from the feed pipe 16 in the bottom of the tank. Thus, in operation, the water passes from the bottom of the storage tank 14 75 through the supply 13, circulating through the circulating units 8 in succession and flowing back into the top of the storage tank 14 through the eduction pipe 15. The water is heated by the influence of the 80 burners 6 as it circulates through the circulating units 8 and passes into the storage tank 14 in its heated condition.

In the drawing, my circulating units 8 are shown of elliptical shape, however it will be 85 understood that they may be made of any suitable shape and form, so long as the principles of the invention are conserved in the construction of the same. There are, however certain elementary features of construction upon which the efficiency and best results from the invention depend, and to which, much importance is attributed. These features will become apparent in the following detail description of the construction and 90 form of the said circulating units. An outer pipe 18 of triangular shape in cross section is in communication with nipples 19 and 20, which nipples are diametrically arranged and receive the connecting pipes heretofore 95 described, the said nipples being interiorly threaded to coöperate with threads on the extremities of the said connecting pipes. Transverse parallel arranged pipes 21 and 22, also of triangular shape in cross section, 100 communicate at their extremities with the outer pipe 18, their communicating points being adjacent the nipples 19 and 20, whereby the water, immediately upon entering the heating unit 8, is distributed through the 105 pipes 18, 21 and 22 and again comes together at the eduction nipple and is discharged 110

through the communicating pipe into the succeeding heating unit, wherein it is again distributed through the various pipes thereof. The pipes 18, 21 and 22 are spaced apart 5 to form relatively narrow openings through the heating unit 8, whereby the flame from the burner is caused to spread out in a relatively narrow jet in its extension from the burner through said openings. This construction of the pipes, to leave these relatively narrow openings, also results in obtaining the greatest degree of efficiency from the heat units for quickly raising the temperature of the water in its passage through 10 15 said pipes. The triangular shape of the pipes 18, 21 and 22, which are positioned on the heating unit so that two sides of each of the pipes converge inwardly toward the burner, cause these spaces to widen out toward the lower side of the heating unit and at the same time to expose a maximum area 20 25 of said pipes to the influence of the heat. For convenience and for the sake of a more definite description, these relatively narrow openings will be designated 23, 24 and 25. The particular shape of these openings has a tendency to create a suction through the heating unit 8, thereby inducing a thorough circulation and mixture of air with the gas. 30 35 40 Thus, instead of diminishing the efficiency of the burners, as has heretofore been the natural result when auxiliary appliances are used, the construction of this circulating unit increases the efficiency as well as to minimize the consumption of gas by the thorough mixture of air therewith. The heating unit is of sufficient area to entirely cover the burner, thereby forming a housing through which a draft is created in substantially the same manner as through the ordinary fire box, the circulating unit entirely confining the flames below the same in the space between the latter and the burner.

By the use of my invention, the same heat employed for cooking is used to heat water, and the employment of auxiliary, or independent water heating means is obviated, resulting in a great saving of fuel.

A further advantage of the invention re-

sides in the prolonged retention of heat on 50 the cooking stove, whereby foods may be left on the stove and kept warm by the hot water in the circulating units for a considerable length of time.

While I have described and illustrated a 55 specific form of the invention, it is understood that the same may be modified and varied without departing from the spirit of the invention or the scope of the appended claims. 60

Having thus described my invention, what I claim and desire to secure by Letters Patent is:

1. The combination with the burner of a cook stove, of a fluid circulating unit disposed above said burner and occupying an area equal to the area occupied by said burner, said circulating unit comprising an outer pipe forming a continuous elliptical passage, nipples mounted on said outer pipe 65 and with which the latter is in communication, said nipples being disposed opposite each other, and parallel connecting pipes communicating at their extremities with said nipples and disposed in substantial alignment with said nipples. 70 75

2. The combination with two burners of a cook stove, of a fluid circulating unit disposed above each of said burners, said circulating units each comprising an outer elliptical shaped pipe forming a continuous passage, an induction and eduction nipple connected with each of said elliptical shaped pipes of said circulating units, a pipe connecting the eduction nipple of one of said 80 circulating units with the induction nipple of the other circulating unit, said nipples of each circulating unit being disposed opposite each other, and a pipe encircled by said outer elliptical shaped pipe and communicating at its extremities with said outer elliptical shaped pipe adjacent the said nipples. 85 90

In testimony whereof, I affix my signature in the presence of two witnesses.

WALLACE WILSON.

Witnesses.
